UNITED STATES PATENT OFFICE

132,890

DESIGN FOR A WALLBOARD FINISHING KNIFE

Willie J. Brabham, Bamberg, S. C., assignor of one-half to James F. Risher, Bamberg, S. C.

Application October 2, 1941, Serial No. 103,614

Term of patent 14 years

To all whom it may concern:

Be it known that I, Willie J. Brabham, a citizen of the United States, residing at Bamberg, in the county of Bamberg and State of South Carolina, have invented a new, original, and ornamental Design for a Wallboard Finishing Knife, of which the following is a specification, reference being had to the accompanying drawing, forming part thereof.

I claim:

The ornamental design for a wallboard finishing knife, as shown.

WILLIE J. BRABHAM.
